Assistant Examiner—T. Chase Nelson

(74) Attorney, Agent, or Firm—Suiter West PC LLO

(57) **CLAIM**

I claim the ornamental design for a combustion nailer, as shown.

DESCRIPTION

FIG. 1 is an isometric view showing my new design;

FIG. 2 is top plan view showing my new design;

FIG. 3 is a front elevation view thereof;

FIG. 4 is a left side elevation view thereof;

FIG. 5 is rear elevation view thereof;

FIG. 6 is a right side elevation view thereof; and,

FIG. 7 is a bottom plan view thereof.
